UNITED STATES PATENT OFFICE.

EDWIN LIST CORNELL, OF WILLESDEN, ENGLAND.

SUPPORTING DEVICE FOR USE IN DARNING.

1,414,182.

Specification of Letters Patent. Patented Apr. 25, 1922.

Application filed March 21, 1921. Serial No. 454,242.

To all whom it may concern:

Be it known that I, EDWIN LIST CORNELL, of 171 Harlesden Road, Willesden, in the county of Middlesex, England, have invented certain new and useful Improvements in Supporting Devices for Use in Darning, of which the following is a specification.

This invention relates to devices for supporting stockings and other articles of clothing during the process of darning holes therein.

Now such supporting devices must satisfy certain requirements to enable them to be used with success; in the first place, the device must support the part of the fabric which is to be repaired by darning, and the material of which has more or less elasticity, in such manner that the fabric is not permitted to stretch or deform immediately around the hole or damaged part, so that the repairs can be effected without alteration of shape of the article or garment; secondly, the supporting surface for the part under repair should be such that for a short distance, at any rate, beneath the under surface of the fabric, the supporting surface should be permeable to the needle, permitting it to pass easily beneath the under surface of the fabric during the darning operation and without catching the darning thread which the needle carries; finally the fabric must be firmly supported, and the supporting appliance must not be expensive in construction and mechanical clamping devices are objectionable in that they require manipulation and increase the cost of manufacture.

Considering a known construction of supporting device composed of a solid mushroom-shaped or convex supporting surface of wood, it will be understood that elastic fabric, such as stockings are composed of, would be extremely liable to become stretched and deformed when held over such a device, and would be inclined to recede from the raised centre of the supporting surface and cause the stretching of the hole in the fabric which is to be repaired, with consequent deformation of the garment.

To obviate some of these disadvantages it has already been proposed to provide a convex supporting surface for the fabric to be darned, which supporting surface has been composed of fibres vertically disposed, and

5 gested. Further in such known devices a holder of wood or other material has been suggested to carry a cushion composed of flexible bristles or fibre, but such constructions have certain disadvantages in use since 60 the pile of the fabric or the flexible bristles of the brush hitherto suggested do not form a foundation calculated to rigidly support the fabric placed upon them when such fabric receives a downward pressure, but are 65 inclined to bend, whereas I have found that the fabric should be more rigidly upheld while at the same time it is highly essential that the supporting bristles or some equivalents therefor should be capable of deflection to permit of the passage of the needle.

According therefore to the present invention, the holder which may be of wood or other material has a head over which the article to be repaired is to be placed and a shank by which the device can be grasped in the hands of the user, and is formed with a central cylindrical recess in the head. Within this recess is fitted the base of a structure composed of practically inflexible 70 parallel wires mounted close together and extending about vertically, the lower ends of the wires being mounted in a resilient or flexible foundation; the upper ends of the wires extend, as hitherto in such devices, 75 slightly above the surrounding wall of the recess in the head and the upper ends of the wires conjointly form a smooth supporting surface for the fabric, and since the lower ends of the said wires are mounted in the 80 resilient or flexible foundation, hereinafter termed resilient foundation, they can be easily rocked or inclined in relation to such foundation and the fabric which they support, to permit of the passage of a needle 85 passing angularly between them without the wires themselves being flexed.

The nature and advantages of this invention will be more clearly understood on reference to the following description of 100 the accompanying drawings illustrating examples of its application.

Fig. 1 represents in elevation a device embodying this invention.

Fig. 2 is a plan of the said device.

Fig. 3 shows a modified form of the device, the left-hand half thereof being shown in elevation, and the right-hand half in section.

The numeral 1 indicates the head of the 110

device, 2 the shank or holder, 3 the recess in the head, 4 the brush-like arrangement of wires, which latter are preferably staples passing through or embedded in the foundation 5, of pliable or resilient material.

The foundation 5 is adhesively secured to the bottom of the recess 3, which bottom is preferably slightly convex, so that the wires in the centre of the device stand above those 10 around the edges, and the latter wires may also if desired project slightly above the peripheral rim of the head of the device, and the upper ends of the wire bristles present conjointly a smooth surface.

15 The mode of use is as follows:—The left hand of the person using the device may be placed inside the stocking or other garment, keeping the worn parts in their normal positions. The improved darning device can 20 then be inverted and placed over the hole in such manner that the bristles of the brush become partly embedded in the fabric, when the device can be held by the fingers of the left hand whilst the sleeve, stocking, or the 25 like is turned inside out. The darning is then performed, the needle and wool passing over the points of the brush bristles, which offer no obstruction to their passage. Meanwhile the parts of the garment surrounding 30 the hole are held against stretching or distortion, so that less wool is used for the repair, and a neater result obtained.

What I claim as my invention and desire to secure by Letters Patent is:—

1. A darning device comprising a plurality of practically inflexible wires arranged in spaced parallel relationship so that their upper ends constitute a supporting surface and means for resiliently securing said wires by their lower ends to permit a free inclination in any lateral direction to each wire. 35

2. In a supporting device for use in darning, the combination of a resilient foundation and a plurality of practically inflexible wires, said wires being mounted each by one 40 end in said resilient foundation, in spaced parallel relation.

3. In a supporting device for use in darning holes in garments, the combination of a recessed head, a holder extending therefrom, 45 a resilient foundation secured in the recess in said head, and a large number of practically inflexible and normally parallel wires secured in said foundation by their inner ends, said wires being capable of lateral 50 movement in any direction to permit of some of said wires assuming an inclined position in relation to adjacent wires.

In witness whereof I have hereunto set my hand in the presence of two witnesses.

EDWIN LIST CORNELL.
